UNITED STATES PATENT OFFICE.

DANIEL KOGLER, OF NEW YORK, N. Y., ASSIGNOR TO MONTAGUE REDGRAVE, OF JERSEY CITY, NEW JERSEY.

DESIGN FOR A GAME-BOARD.

SPECIFICATION forming part of Design No. 27,443, dated July 27, 1897.

Application filed May 25, 1897. Serial No. 638,164. Term of patent 14 years.

To all whom it may concern:

Be it known that I, DANIEL KOGLER, a citizen of the United States, residing at New York, in the county of New York and State of New York, have invented and produced a new and original Design for Game-Boards; and I do declare the following to be a full, clear, and exact description of the same, reference being had to the accompanying drawing, forming a part thereof.

This is a design for game-boards provided with series of holes for pegs, the location of such pegs being governed by the throwing of dice and guided by numerals arranged on the board alongside of the holes respectively.

The accompanying drawing represents a plan view of a game-board embodying and presenting my design.

The leading feature of the said design is a central circular series of holes and four diagonal radiating series, each hole having a numeral beside it and the circular series being in the border of a disk of different color from the remainder of the ground of said board, an angular figure approximating a square of a still different color occupying the central part of the disk.

A designates the ground of the board, which is square, with a rim B raised along its sides.

C designates the central disk, having a narrow border C', in which twenty-eight holes d are arranged to form a circle. This series is divided into four sets of seven and arranged around the circle, each numeral being on the inner side of the hole which it indicates. Four straight series of holes D radiate from the said circular series toward the corners of the board. Each series D consists of ten holes. In the very center of the disk C is a superposed four-sided figure E, approximately a square, with inwardly-curving sides having a narrow border e.

Having thus described my design, what I claim as new, and desire to secure by Letters Patent, is—

The design for a game-board herein shown and described.

In testimony whereof I affix my signature in presence of two witnesses.

DANIEL KOGLER.
